DESIGN FOR A COMBINED SCORE TABLE, SCORE PROJECTOR, AND SEAT UNIT

Andrew L. Henkel and Burke M. Ewing, Chicago,
Ill., assignors to The Brunswick-Balke-Collen-
der Company, Chicago, Ill., a corporation of
Delaware

Application November 25, 1940, Serial No. 96,778

Term of patent 14 years

To all whom it may concern:

Be it known that we, Andrew L. Henkel and Burke M. Ewing, both citizens of the United States, both residing in the city of Chicago, in the county of Cook, State of Illinois, have invented a new, original, and ornamental Design for a Combined Score Table, Score Projector, and Seat Unit, of which the following is a specification, reference being had to the accompanying drawing, forming a part thereof.

Figure 1 is a perspective view of a combined score table, score projector, and seat unit, or similar article, showing our new design;

Figure 2 is a side elevational view thereof;
Figure 3 is a front elevational view thereof;
and

Figure 4 is a top plan view thereof.

The opposite side of the device is substantially the same as that shown.

We claim—

The ornamental design for a combined score table, score projector, and seat unit, or similar article, as shown and described.

ANDREW L. HENKEL.
